UNITED STATES PATENT OFFICE.

ADELMER M. BATES, OF CLEVELAND, OHIO.

MACHINE FOR PRINTING BAGS.

No. 918,496.

Specification of Letters Patent.

Patented April 20, 1909.

Application filed February 20, 1907. Serial No. 358,483.

To all whom it may concern:

Be it known that I, ADELMER M. BATES, a citizen of the United States, residing at Cleveland, in the county of Cuyahoga and State of Ohio, have invented a certain new and useful Improvement in Machines for Printing Bags, of which the following is a specification.

My invention relates to bag machines and particularly machines adapted for use in reversing, filling and printing bags, as illustrated in the accompanying drawings.

In most of the drawings parts have been omitted for it is thought that they would otherwise lead to confusion.

Figure 1 is a side part sectional view; Fig. 2, a front elevation; Fig. 3, a detail side view; Fig. 4, a front detail of the bag carrier on line 4-4 of Fig. 1; Fig. 5, a rear detail view of the bag carrier; Fig. 6, a cross section on the line 6-6 of Fig. 5; Fig. 7, a diagrammatic view of the double press apparatus; Fig. 8, a detail of the bag supports, and Fig. 9, a cross section on the line 9-9 of Fig. 8.

Like parts are indicated by the same numerals in all the figures.

1 is the standard or base on which the operative parts are mounted.

2 is a shaft mounted therein having the fly-wheel 3 at one end and the fast and loose pulleys 4 at the other. This shaft carries a pinion 5 which meshes with the gear wheel 6 which is journaled on the frame at 7, carries the cam 8, and drives the bar 9 which is eccentrically pivoted at one end on such gear wheel. This gear wheel I call the drive wheel. The bar 9 is pivoted at the other end to a frame 10 which carries two double row inking devices 11-11 each elastically drawn toward the frame by the springs 12, 12. The frame 10 extends across the machine and on the opposite side from that shown in Fig. 3, for example, is provided with an upward projection 13 pivotally connected to the arm 14 which is downwardly bent as indicated, and the other end of which is pivoted at 15 to the frame. Pivoted on this last mentioned side of the machine is an eccentric plate 16 mounted in the same axial line as the gear wheel 6 and eccentrically pivoted thereto is the rod 17 which is pivoted in the same manner as rod 9 at the other end of the frame 10.

Pivoted to the bottom of the frame 1 is

the frame 18 having the inking pad 19 and the printing face 20 thereon. I do not show the details of such inking pad or printing face, but it will be understood that suitable ink supplying devices are associated with the pad to keep the inking rolls 11, 11 properly inked and the printing face will be adapted to receive the type or plate which is to impart the impression. As the gear wheel 6 rotates with its associated cam plate 16, the two rods 9 and 17 will tend to rock the frames 10 and 18 to and fro, but since the frame 10 is related as indicated to the arm 14 it will swing on the axis 21, which axis is the line of pivotal connection between the frame 10 and the rods 9 and 17. Thus the inking rolls will travel back and forth over the printing surface and the inking pad. These parts are very similar to those of well known types of printing machines. The arm 14, however, is bent down for the reason hereinafter set forth.

Rising from the upper part of the frame 1 is a support 22 which carries the pin 23 on which the parts now to be described are mounted. The first of these parts is the bag carrying device consisting of the central plate 24 and arms projecting therefrom. One set of these arms 25, 25 are adjustably secured by means of the slots 26, and the thumb screws 27. Another set 28 are pivoted at 29 and their inner ends are formed in the shape of elbow crank levers 30 which overlap as indicated in Fig. 5, and they are flexibly drawn together by the spring 31. Each pair of adjacent arms 25 and 28 form together a bag holding device. As herein-after explained, the bag may be reversed or turned on this bag holding device so that it becomes also a bag turning device.

A modification of this structure is shown in Figs. 8 and 9 where, for each of the arms 25, I substitute a broad platen 32 which is secured adjustably in like manner by the slot 26 and thumb screw 27. 33 is a bag shown in position on the bag holder in several of the figures. The platen last described is especially useful where the bags are to be printed on both sides and the structure for doing that is diagrammatically illustrated in Fig. 7, where a duplicate of the printing device, which, taken as a whole, is mounted on frame 18, is shown as mounted on frame 34. Of course, the connections and driving parts would, in the case of the use of two printing

devices, require to be changed from that shown in the drawings, but such changes would readily occur to any mechanic. All that is necessary for my purpose is to indicate that two such printing devices might be employed, one to print on one side, and the other to print on the other side of the bag simultaneously. Details of structure which I am here illustrating relate only to the operation of one printing device and the simultaneous and related operation of the bag handling device. Returning now to the bag holding devices and referring to those illustrated at the top of the drawing, it will be found that two holders of a given pair are inclined toward each other and that the bag can, therefore, be easily slipped onto its holder where it hangs in the loose position as indicated in Fig. 2. To stretch the bag it is only necessary to move one holder of each pair away from the other and this occurs when the spring 31 is left free to act as is the case at the left of Fig. 5 and the right of Fig. 2.

Assuming now that the machine is in the position shown in Fig. 2 with certain stretched bags in position and other loose bags in position, it is necessary in order to bring the stretched bags down where they can be printed to turn the bag carrying device in the direction indicated by the arrow in Fig. 2. This is done by the following mechanism: 35 is an arm pivoted on the frame at 36 and held in the position shown in Fig. 1 by the spring 37 against the stop 38 on the frame 1. Pivoted to this arm is the rod 39 which is connected to the elbow crank lever 40 which is pivoted to the support 22 and is pivotally connected at the end of its other branch to the rod 41 which is pivoted to the arm 42 on the collar 43, mounted on the sleeve 44, which is pivotally mounted on the pin 23. On the same sleeve 44 is secured the plate 24 which carries the bag holding devices. This is the part which must be turned to bring the stretched bags into position for printing. When, in the course of the operation of the machine the arm 35 is engaged by the pin 45 on the frame 10 as indicated in Fig. 1, the further motion of the machine will bring the arm 35 to the position shown in dotted lines in Fig. 1 and this will draw down on the rod 39, rock the elbow crank lever 40 and turn the collar 43. The pin in the outer portion of the arm 42 is adapted to engage the recess preferably shaped as indicated in dotted lines in Fig. 4, in the dog 46 which is pivoted at 47 on the support 22 and inwardly drawn by the spring 48. Its end, therefore, lies between the ends of two of the four cams 49, 49. A second dog 50 is pivoted on the arm 42 and is adapted to engage one of four projections 51 on the hub associated with the plate 24. As the rod 39 descends, the rod 41 is drawn to the right as indicated in Fig. 4, thus first forcing the dog 46 backward and out of engagement with the cam 49 and then bringing the dog 50 into engagement with the projection 51 whereby the plate 24 is rotated and the parts are so adjusted that it will travel ninety degrees and bring the next set of stretched bags down between or into proper relation to the printing mechanism. Here the bags will be printed by the continuance of the operation either on one side or both sides, by the assistance of the double printing device when employed, and the assistance of the wide inner platen of Figs. 7, 8 and 9 when that is employed. As soon as the bags are thus printed they should be released or discharged and this will be accomplished by bringing the stretching arms and platen quickly together. This is accomplished by the mechanism which I shall now describe.

Assuming that the bag stretching or holding devices are in the position indicated in Fig. 5, and having reference to those at the lower part of the drawing where they may be supposed to hold a bag which has just been printed on one or both sides, the object is to quickly release these bags so that they may fall off before the upper rotation of their holders begins. This will be done by bringing the cam 59 quickly around in the direction indicated by the arrow in Fig. 5 against the upper ends of the elbow crank levers 30 whereby the spring 31 will be stretched and the bag holding arms 28, 28 will be thrown toward their associated bag holding arms. The tension on the bag will be released and the bag discharged.

The cam is moved by the following means. Pivotedly mounted on a bracket on the frame or fixed part of the machine is the bar 60, the end of which lies in the pathway of the cam 8. To it is pivoted the rod 61, the upper end of which is pivoted to one end of one branch of the elbow crank lever 62 which is pivoted on the frame 22, while the other end of the elbow crank lever is pivoted to the rod 63, the other end of which is pivoted to the projection 64 on the collar 65. To this projection 64 is secured the spiral spring 66, the other end of which is fastened to the support 22 by a pin 100. Now, the collar 65 is fastened by the set screw 67 to the sleeve 44, to the other end of which is permanently secured the cam 59. The parts are so related that when the stretched bags have been printed, the cam 8 engages the lower end of the arm 60, raises it, moves the several parts until the cam 59 is quickly drawn around in the direction indicated by the arrow in Fig. 5, and depresses the lower ends of the elbow crank levers 30, thus releasing the bags by a sudden or jarring motion so that they are quickly discharged from their holders. Al-

most simultaneously with this action the operation of lifting the dog 46 out of engagement is performed. The parts are moved forward another quarter of the rotation whereby the dog 46 drops in between two of the cams 49 and the parts are again locked in position.

The use and operation of my invention are as follows: The bags are put upon the bag holders as these rise to the top of the machine, and if the bags are to be reversed this can be done in the usual way by drawing them down over the bag holding arms. The action of the apparatus then starts machinery forward and the bags on the arms are turned down toward the right where if so desired and the construction be as shown, they will be stretched. In any event, they will be carried downward. They will then, by the next step, be carried to the lower part of the machine where they will be in position to be printed on one or both sides and on the bags stretched or otherwise and on the inner platen if that be used. The next forward step of the apparatus throws the printed bags off and so the operation continues. This apparatus furnishes means for turning the bags, for holding them, for feeding them to the press, for printing them and discharging them and it requires no higher grade labor than what is necessary to turn the bags or run them on the turning arms. The character of the apparatus may be better understood when I explain a little further the subject to which it relates. Bags may be printed in the roller before they are made, but this involves numerous difficulties not here necessary to be discussed. The completed bags may be printed on ordinary printing presses but this involves great difficulties as will be seen at a glance. The prevailing practice is to print the bag blank on a cylinder press and then make up the bag. Now when this is done, it is obvious that the manufacturer must carry in stock a quantity of printed bags or the user must keep a large stock in advance or there will be considerable delay in filling an order, because the bag has to be made from the blank which is first printed. Moreover, in this method expensive help is required to operate the cylinder press and expensive plant is necessary and the user cannot well print his own bags. By my system and apparatus the bag is printed while it is carried by the holder on the arms of which it has been turned. Thus the manufacturer, dealer, or user may have a quantity of blank bags and when called on to print for a certain special order he has only to run them through the printing press, associated with the bag turning device and the work is done. Thus I obviate delay and the carrying of stock. By stretching the bags or spreading them over the inner platen, the printing is most ef-

fectually and accurately done and the bags can be printed on both sides, especially where the inner platen is used.

I claim:

1. In a bag machine, the combination of a movable bag holder with a printing press and means for bringing them into operative relation, said bag holder comprising two parts movable from each other and adapted to enter the bag and stretch it from within. 75

2. In a bag machine, the combination of a movable bag holder with a printing press and means for bringing them into operative relation, said bag holder comprising two parts, one of which is a flat platen which 80 enters the bag to stretch the same from within.

3. In a bag machine, the combination of a two part printing press carrying two printing faces with a bag holder adapted to move the bag between the presses so that both sides are printed at once, said bag holder containing a broad, flat platen inside the bag. 85

4. In a bag machine, the combination of a two part printing press carrying two printing faces with a bag holder adapted to move the bag between the presses so that both sides are printed at once, said bag holder adapted to stretch the bag from within. 90

5. In a bag machine, the combination of a two part printing press carrying two printing faces with a bag holder adapted to move the bag between the presses so that both sides are printed at once, said bag holder containing a flat platen adapted to enter the bag and stretch the same from within. 100

6. In a bag machine, the combination of a two part printing press carrying two printing faces with a bag holder adapted to move the bag between the presses so that both sides are printed at once, said bag holder comprising two parts which move away from each other and one of which is a flat platen, said parts adapted to enter the bag and stretch it from within. 105

7. In a bag machine, the combination of a printing press with a bag holder comprising parts over which the bag may be turned and on which it is carried and means for moving the holder into operative relation to the press. 115

8. In a bag machine, the combination of a printing press with a movable bag holder, means for bringing the bags on the holder successively into operative relation to the press, means for stretching the bags and means for releasing them from the holder after they have been printed. 120

9. In a bag machine, the combination of a printing press with a movable bag holder comprising a rotary part with bag holding arms projecting rotatably therefrom, means for bringing the bags on the holder successively into operative relation to the press, 125

- means for stretching the bags on their separate holders and means for releasing the bags from said holders when the latter are downwardly directed. 65
5. 10. In a bag machine, a bag holding device comprising a plate set in a vertical plane, a series of bag holding arms mounted thereon, means for rocking some of the arms to stretch the bags and means for retracting 70
10 said arms to release the bags.
11. In a bag machine, a bag holding device comprising a plate set in a vertical plane, a series of bag holding arms mounted thereon, means for rocking some of the arms 75
15 to stretch the bags and means for retracting said arms to release the bags, said means comprising a cam which normally holds some of the holding arms in retracted relation and is capable of forward movement
20 out of its normal position to retract another set of said arms.
12. In a bag machine, a bag holding device comprising a plate set in a vertical plane, a series of bag holding arms mounted 80
25 thereon, means for rocking some of the arms to stretch the bags, and means for retracting said arms to release the bags, said means comprising a cam which normally holds some of the holding arms in retracted relation and is
30 capable of forward movement out of its normal position to retract another set of said arms, and means for operating the cam in response to the movement of the press. 85
13. In a bag machine, a bag holder comprising a plate in a vertical position with a series of bag holding arms thereon adapted to be inserted in the bags, one arm of each pair being movable and opposing means for holding said movable arm at varying 90
35 distances from its associated fixed arm, said means consisting of a spring which draws the movable arm in one direction and a cam which forces it in the other. 100
14. In a bag machine, a bag holder comprising a series of bag stretching arms received into the bag and on which the bag is held with means for suddenly retracting said arms to release and discharge the bag. 105
15. In a bag machine, the combination of 110
50 a movable bag carrier with a series of bag holders thereon adapted to be inserted in the bags, means for automatically locking the bag carrier in a definite position and means for automatically releasing it and carrying
55 it forward a definite distance to feed the bags.
16. In a bag machine, the combination of 115
55 a rotary bag feeding device with a series of bag holders thereon, adapted to stretch the bag from within and mechanism to alternately stretch and relax the bags and to rotate the feeder forward. 120
17. In a bag machine, the combination of a printing press with a swinging frame a
connection from the swinging frame to the fixed frame and a rod from such connection to the feeding mechanism and a bag feeding and holding device which engages the bag from within operated by such feeding mechanism to bring the bags successively into operative position with reference to the press, said feeding mechanism containing a locking dog and a feeding dog and means for successively operating them. 65
18. In a bag machine, the combination of 75
a printing press with a swinging frame, a connection from the swinging frame to the fixed frame and a rod from such connection to the feeding mechanism and a bag feeding and holding device which engages the bag from within operated by such feeding mechanism to bring the bags successively into operative position with reference to the press, said feeding mechanism containing a fixed locking dog, a movable feeding dog and means 80
85 for first releasing the locking dog and then moving the feeding dog forward.
19. In a bag machine, the combination of 90
a rotating bag feeding device with a series of bag holders thereon, consisting of parts which enter the bag and are adapted to stretch the same and means for moving said parts with reference to each other to alternately stretch and release the bag. 95
20. In a bag machine, the combination of 95
a rotating bag feeding device with a series of bag holders thereon, consisting of parts which enter the bag and are adapted to stretch the same and means for moving said parts with reference to each other to alternately stretch and release the bag, said means containing a spring which tends to move one of the stretching parts in a given direction. 100
21. In a bag machine, the combination of 105
a rotating bag feeding device with a series of bag holders thereon, consisting of parts which enter the bag and are adapted to stretch the same and means for moving said parts with reference to each other to alternately stretch and release the bag and a cam 110
110 which tends to move such moving part in the opposite direction.
22. In a bag machine, the combination of 115
a rotating bag feeding device with a series of bag holders thereon, consisting of parts which enter the bag and are adapted to stretch the same and means for moving said parts with reference to each other to alternately stretch and release the bag and a cam which tends to move such moving part in the 120
opposite direction, said cam moved in one direction by a spring and in the other by a driven part.
